Application July 15, 1948, Serial No. 147,634

Term of patent 3½ years

(Cl. D85—2)

To all whom it may concern:

Be it known that we, Ernest Sohn (1) and Edward San Giovanni (2), both citizens of the United States of America, residing at (1) New York, county of New York, and State of New York, (2) at Ridgefield, in the county of Fairfield and State of Connecticut, have invented a new, original, and ornamental Design for a Combined Cigarette and Lighter Holder, of which the following is a specification, reference being had to the accompanying drawing, forming part thereof.

Fig. 1 is a front view of a combined cigarette and lighter holder, showing our new design.

Fig. 2 is a top plan view of Fig. 1 taken along the line 2—2 thereof.

Fig. 3 is a rear view thereof.

What we claim is:

The ornamental design for a combined cigarette and lighter holder, as shown.

ERNEST SOHN.

EDWARD SAN GIOVANNI.
